WINDOW BRACKET

Fred C. McDowell, Naches, Wash.

Application May 28, 1940, Serial No. 337,720

3 Claims. (Cl. 156—23)

This invention appertains to new and useful improvements in window brackets for supporting shades, curtains and drapes.

The principal object of the present invention is to provide a support for curtains, shades and drapes which can be firmly clamped in place against the window frame facing without the use of nails or other elements that would mar the front of the window facing.

Another important object of the invention is to provide a support of the character stated wherein the various elements employed can be readily adjusted to accommodate the items to be mounted.

These and other objects and advantages of the invention will become apparent to the reader of the following specification.

In the drawings:

Figure 1 is a fragmentary front elevational view of the structure mounted on a window.

Figure 2 is a fragmentary top plan view of the structure mounted on a window.

Figure 3 is a section taken substantially on a line 3—3 of Figure 1.

Figure 4 is a section taken substantially on a line 4—4 of Figure 1.

Figure 5 is a side elevational view of the rod.

Figure 6 is a sectional view taken substantially on a line 6—6 of Figure 2.

Figure 7 is a sectional view taken substantially on a line 7—7 of Figure 1.

Figure 8 is a fragmentary side elevational view showing a support especially adapted for Venetian blinds.

Figure 9 is a sectional view on a line 9—9 of Figure 8.

Referring to the drawings, wherein like numerals designate like parts, it can be seen that numeral 5 represents an elongated rod having its end portions threaded as at 6.

An L-shaped window shade roll supporting arm 7 has its upper apertured end slipped over each threaded end portion 6 and is secured in the desired position on the rod by jamb nuts 8. Each arm 7 has either a round opening or a slot 9 therein.

Spaced outwardly from the arm 7 on the threaded portion 6 is the curtain rod supporting socket which is in the form of a tube 10 apertured at its intermediate portion to receive the threaded portion 6 of the rod 5 and jamb nuts 11 are provided on the threaded portion of the rod at each side of the socket tube 10 to fix the location of the socket and prevent longitudinal adjustment of the same on the rod. The up-

wardly disposed tubular ends of the sockets 10 are adapted to receive the downturned ends of a curtain rod (not shown) in a position for supporting said rod on the device.

5 A clamp plate 12 is provided on each threaded portion 6, each clamp plate having an opening for receiving the threaded portion of the rod 5 and having a spur 13 which can be driven into the edge portion of the window facing 14. Jamb nuts 15 are provided on the threaded portion of the rod, one at each side of the plate 12 to secure the plate in engaged position with the window facing.

Hook members 16 adapted to support the ends of a pole from which drapes can be hung, are each provided with a shank adapted to fit into a socket tube 17 which is mounted substantially as are the tubes 10. The threaded portion of the rod 5 passes through the corresponding tube 17 and a jamb nut 18 is provided on the threaded portion of the rod at each side of the tube 17 for fixing the position of the tube 17 on the rod.

An ornamental cap 19 can be provided for each end of the rod 5.

20 A support such as is shown in Figures 8 and 9 and generally referred to by numeral 20 is especially adapted for supporting Venetian blinds. This support 20 includes the elongated rod 21 having the threaded end portions 22—22 and on each threaded end portion is the block assembly 23, which consists of a block 24 and a plate 25 which is bent to provide the depending flanges 26—26 formed with spurs 27 driven into the opposite sides of the block 24. The top of the plate 25 is formed to provide the barrels 28 through which the threaded portions of the rod 21 is disposed. Jamb nuts 29 are provided on the threaded portions 22, one at each end of the corresponding plate 25, to hold the corresponding unit 23 against self-adjustment on the rod 21. The head bar of the Venetian blind generally referred to by numeral 30 can be secured to the block 24 in any desired manner.

25 U-shaped members 32 are provided at the ends 45 of the rod, each provided with a spur 33 adapted to be driven into the window frame.

The ends of the rod 21 extend through openings in the bight portion of the U-shaped members 32 and jamb nuts 34 are provided at each end portion of the rod 21 to prevent self-adjustment of the U-shaped members 32 on the rod.

50 While the foregoing specification sets forth the invention in specific terms, it is to be understood that numerous changes in the shape, size and materials may be resorted to without de-

parting from the spirit and scope of the invention as claimed hereinafter.

Having described the invention, what is claimed as new is:

1. A supporting structure for windows comprising an elongated rod having threaded portions, article supporting elements on the threaded portions of the rod, and clamp plates on the threaded portions, each of the said threaded portions having jamb nuts thereon, one at each side of the corresponding clamp plates to prevent self-adjusting of the clamp plates.

2. A supporting structure for windows comprising an elongated rod having threaded portions, article supporting elements on the threaded portions of the rod, and clamp plates on the threaded portions, each of the said threaded portions having jamb nuts thereon, one at each side of the corresponding clamp plates to prevent self-adjusting of the clamp plates, and ad-

ditional jamb nuts on the threaded end portions of the rod for engaging opposite sides of the supporting members to prevent longitudinal adjusting of the same on the rod.

3. A supporting structure for windows comprising an elongated rod having threaded portions, article supporting elements on the threaded portions of the rod, and clamp plates on the threaded portions, each of the said threaded portions having jamb nuts thereon, one at each side of the corresponding clamp plates to prevent self-adjusting of the clamp plates, said supporting members each consisting of a block, a plate secured to the block and including a barrel through which the rod extends, and jamb nuts on the threaded portion of the rod for engaging opposite ends of the plate to prevent self-adjusting of the member.

FRED C. McDOWELL.
